Primary Examiner—A. Hugo Word*Assistant Examiner*—I. Simmons*Attorney, Agent, or Firm*—Flynn, Thiel, Boutell & Tanis**[57] CLAIM**

The ornamental design for a low frequency muscle relaxer, as shown and described.

DESCRIPTION

FIG. 1 is a front elevational view of a low frequency muscle relaxer showing our new design;
FIG. 2 is a rear elevational view thereof;
FIG. 3 is a top plan view thereof;
FIG. 4 is a bottom plan view thereof;
FIG. 5 is a side elevational view thereof;
FIG. 6 is a side elevational view thereof, opposite that shown in FIG. 5; and,
FIG. 7 is a perspective view thereof.
